UNITED STATES PATENT OFFICE.

GEORGE E. STEVENS, OF LYNN, MASSACHUSETTS, ASSIGNOR TO GENERAL ELECTRIC COMPANY, A CORPORATION OF NEW YORK.

ELECTRIC HEATER FOR LIQUIDS.

No. 812,609.

Specification of Letters Patent.

Patented Feb. 13, 1906.

Application filed July 19, 1904. Serial No. 217,219.

To all whom it may concern:

Be it known that I, GEORGE E. STEVENS, a citizen of the United States, residing at Lynn, county of Essex, State of Massachusetts, have invented certain new and useful Improvements in Electric Heaters for Liquids, of which the following is a specification.

The present invention relates to electric heaters of the type employed in heating and boiling liquids for cooking and similar purposes; and it has for its object to produce a device which is simple and compact in structure and efficient in operation. To this end I preferably employ a resistance unit of compact structure which may be heated to a high temperature without deterioration and incase the same in an envelop of metal, which is adapted to project into the liquid to be heated. The unit is preferably closely fitted within the envelop, so as to be in good heat-conductive relation thereto, and the leads are brought out through one end of the envelop, the lead from the distant end preferably extending through the center of the unit. It is obvious that a unit of this type may be used in various relations, either independent of or in fixed relation to a liquid-containing receptacle. In the present application I have illustrated one embodiment of the invention consisting of a simple water-heater in which the unit-containing envelop is formed integral with the receptacle and the circuit-leads extend out through the handle.

The nature of my invention will be better understood by reference to the following description, taken in connection with the accompanying drawings, and its scope will be particularly pointed out in the appended claims.

In said drawings, Figure 1 is a side elevation of said water-heater, embodying the features of my invention. Fig. 2 is a central section through the same. Fig. 3 is a bottom view illustrating particularly the means for holding the parts in place. Fig. 4 is a fragmentary view similar to Fig. 2 of the modification; and Fig. 5 is a detail view of said modification, illustrating the means for clamping the handle in position.

Referring in detail to the drawings, 10 designates the receptacle for the liquid, which may be of any preferred form and is here shown as a cylindrical cup provided with a

flange 11, which constitutes a supporting-base. Located centrally within this cup and extending through an opening in its bottom is the heating member 12, which is preferably tubular in shape, with its upper end closed and its lower end firmly secured to the bottom of the receptacle, so as to provide a watertight joint. The lower end of this member 12 is left open, so that the heating unit 13 may be readily slipped into and out of place. This unit may be of any preferred form; but it preferably consists of a helical conducting-ribbon 14, wound on edge with its convolutions insulated from each other and the interior of the heating member 12 by any suitable insulation, but preferably a refractory insulation—for instance, one composed of kaolin and silicate of soda. In the present instance this coil of conducting-ribbon is slipped over a tube 15 of porcelain or other similar insulating material provided with a flange 16 at its lower end, upon which the ribbon is firmly seated. In assembling, a suitable lead 17 is connected to the lower end of the resistance-conductor before the same is passed over tube 15, said lead having first been passed through an opening 18 in the lower end of the tube communicating with a longitudinal groove 19, which extends throughout the length of the tube. The conductor may then be slipped into place upon the tube 15, and the connection between the lead 17 and the conductor 14 will pass down through the groove 19 and when in final position will be located within the winding 13 in a protected position. The other terminal 20 is passed through the center of the tube 15 and through a small opening 21 in a conducting-disk 22 at the upper end of the winding, suitable electrical connections being made between said lead 20 and the disk 22 and said disk and the upper end of the helical winding 14. With this construction the unit 13 may be readily slipped into position in the heating member 12 or drawn out for the purpose of repair.

The unit 13 is preferably held in place by means of a cap 23, which is removably fitted into the lower end of the tubular member 12. 100 This cap is provided with an opening at one side, through which extends a hollow stem 24, which passes laterally through the flange 11 and then upward and outward, so as to form

a handle for the receptacle, the outer end of the stem being provided with a grip 25. The hollow stem 24 serves as a duct for the resistance-leads 17 and 20, which are suitably 5 insulated from each other and the interior of the tube. The parts are firmly held in place by means of an apertured plate 26, which engages at one end with an inturned portion 27 on the flange 11 and at its opposite end is 10 held in place by a screw 28, which passes through the shell of the stem 24. It is obvious that the parts may be held in place by other means. In Figs. 4 and 5 I have shown a modification in which the base 11^a of the receptacle consists of a casting into which the shell 10^a of the receptacle is seated and through which the lower end of the stem 24^a is securely held by reason of the greater thickness of the metal at the point through 15 which the stem passes. The upper end of the stem 24^a is held in place by a sliding member 30, which is provided with oppositely-extending wings which pass under the clips 31, secured to the shell of the receptacle. The 20 wings of the sliding member 30 are provided with projecting portions which engage coöperating depressions in the clips 31 and can be removed therefrom only by springing said wings out of engagement therewith. 25

30 It will be apparent from the above that at any time the stem 24 or 24^a and the cap 23 may be removed for the purpose of withdrawing the resistance unit 13. It will also be apparent that the heating member 12, which is 35 practically surrounded by the liquid to be heated, is in good heat-conductive relation to the resistance-winding 14 and that said member by reason of its smooth exterior permits the receptacle to be readily cleaned.

40 It is obvious that the heating member 12 might also project into the liquid from any of the other walls of the receptacle than the bottom and that the same might be greatly varied in shape without departing from the 45 spirit and scope of the present invention; but it is desirable that the same should be of such shape that the heating unit may be withdrawn for the purpose of repair. It is also desirable that the shape of the heating unit 50 be similar to that of the interior of the heating member 12 in order that the resistance-conductor may be brought into good conductive relation to said member. In the use of the device the level of the liquid should normally be above the upper end of the heating member 12 in order to prevent the unit from becoming unduly heated, thereby failing to utilize fully its energy.

Many uses of the construction of the heating unit and inclosing envelop herein disclosed will be suggested to those skilled in the art as falling within the spirit and scope of the present invention. Many alterations and modifications may also be made in said 65 structure without departing from the spirit

and scope of the invention. I therefore do not wish to be limited to the specific uses or to the specific construction herein disclosed.

What I claim as new, and desire to secure by Letters Patent of the United States, is— 70

1. An electric heater comprising a receptacle, a hollow heating member extending upward from the bottom of the receptacle and open to the exterior of the receptacle at its lower end, an electric heating unit adapted to be inserted in and withdrawn from said member and having its resistance element in intimate thermal relation to the walls of said member, a lead extending from the upper end of the unit down through its center, and a second lead secured to the lower end of said unit. 75

2. An electric heater comprising a receptacle adapted to contain a liquid to be heated, a closed reentrant metallic tube extending upward from the bottom of said receptacle, a resistance unit mounted in said tube in good heat-conductive relation to the walls thereof, the resistance being provided with a joint within the tube below the normal liquid level to prevent burning out. 80

3. In an electric heater, a hollow heating member adapted to extend into the liquid to be heated, an edgewise-wound resistance unit located therein in heat-conductive relation to the walls thereof, comprising a central insulating-tube provided with a flange at one end upon which said resistance-winding is seated, a conducting-disk connected to the opposite end of said winding and resting upon the opposite end of said tube, a lead secured to said disk and extending through said tube, and a second lead secured to the outer end of the resistance unit. 90

4. An electric heater comprising a receptacle, a hollow tubular member within the receptacle extending upward through its bottom and closed at its upper end, an electric heating unit therein, comprising a heating-coil in close heat-conductive relation therewith, and means for removably holding said unit within said member. 100

5. An electric heater comprising a receptacle, a hollow tubular member within the receptacle extending upward through its bottom and closed at its upper end, an electric heating unit therein, comprising a coil corresponding in shape with said tubular member and in close heat-conductive relation therewith, means for removably holding said unit within said member, said means comprising a cap, a duct engaging therewith and communicating with the interior thereof, and a retaining member engaging the base of said receptacle and secured to said duct. 115

6. An electric heater comprising a receptacle, a hollow tubular member within the same extending upward through its bottom and closed at its upper end, a removable electric heating unit therein, a cap for closing 130

the lower end of said member, a duct communicating with the interior of said cap and extending outward to form a handle for said receptacle, and means for securing said cap and said duct in removable relation with said receptacle.

7. An electric heater comprising a receptacle, a hollow tubular member within the same extending upward through its bottom and closed at its upper end, a removable electric heating unit therein, a flange forming the base of the receptacle, a cap for closing the lower end of said member, a duct engaging

said cap and communicating with the interior thereof and extending outward to form a handle, and means for securing said cap and said duct in removable relation with said receptacle comprising a retaining member engaging said flanged base and secured to said duct.

In witness whereof I have hereunto set my hand this 18th day of July, 1904.

GEORGE E. STEVENS.
